UNITED STATES PATENT OFFICE

1,972,646

ACETYLENE GAS GENERATOR

Charles de La Rochette, Neuilly-sur-Seine,
FranceApplication March 2, 1929, Serial No. 343,864
In France March 6, 1928

1 Claim. (Cl. 48—17)

My invention relates to an acetylene gas generator of simple construction and complete safety which may advantageously feed a motor or a blow torch operating by suction.

5 The principle upon which the present gas generator is based consists in the passage of atomized water or of water saturated air which is brought in contact with the calcium carbide through the underpressure created by the suction of the motor or of the blow torch.

10 The water may be atomized either by means of a small injector drawing in water and air by suction or simply by means of a tube immersed in the water contained in a receiver, the admission being preferably controlled by means of 15 a needle valve. Alternately, air saturated with water may be caused to pass by suction also through a porous material immersed in said water or simply upon said porous material such 20 as cotton fabric for example arranged in the shape of a coil or the fabric staggeredly arranged.

When the apparatus is used in combination 25 with a motor, the water from the combustion gases may be condensed and air saturated with said steam may be caused to pass by suction in contact with the calcium carbide; steam only or condensed water may also be used in the same manner.

30 The appended drawings show by way of example various modes of execution of my invention.

Fig. 1 is a part longitudinal sectional view of a first type of apparatus.

35 Fig. 2 is a side elevation of same.

Figs. 3 and 4 are respectively a part longitudinal sectional view and a side elevation of a modified form of apparatus.

40 Fig. 5 is a side sectional view of part of a further modification showing particularly a hydraulic valve.

Fig. 6 is a transverse sectional view of another modified form.

45 Fig. 7 is a longitudinal sectional view of a third mode of execution.

Fig. 8 is a transverse sectional view of a fourth mode of execution designed more particularly for use with an aircraft motor.

Fig. 9 shows an engine with the carburetter, 50 Fig. 7, applied thereto.

Fig. 10 is a cross section of Fig. 7.

The apparatus shown in Fig. 1 which has been 55 designed for working with atomized water comprises a container *a* one end of which is provided with an inlet tube *b* in which the suction

tube *c* for the water leading to the injector *d* is immersed. The apparatus is provided at its other end in the water compartment *e* with an hydraulic valve of any suitable kind, which causes the gas to pass through an orifice *i* near 60 the top of compartment *e* and through the water before it escapes at *j*. Said valve ensures the absolute safety of the apparatus in case of back firing, and serves at the same time as gas purifier.

65 As will be seen in Figs. 1 and 3, the valve *e* is constituted merely by a float *g* perforated at *g*¹; *h* is a flexible tube which allows the movements of the float and connects the float to a stationary tube *h*² that passes out of compartment *e* at *h*³ and connects outside the water compartment with discharge *j*. A water-tight door *o* closes the container *a*.

70 In the modification shown in Fig. 5, the tube *h* is replaced by a small rubber cover *h*¹ of great 75 flexibility which follows every movement of the float. In both the above described valves, the float is designed to allow of using the same water as that of the container, the pressure of which water acting against the suction is continuous. 80

85 A small receptacle filled with a purifying mixture of any appropriate kind may be combined with said valve for eliminating the hydrogen sulphide gas; the same result may be obtained by adding to the calcium carbide ½% of iron oxide. A blow-off cock may be provided at the lower end of the valve.

When the motor or the injector of the blow pipe are started the partial vacuum thus produced causes the instantaneous atomizing of the 90 water by the injector and the production of gas in the carbide container *i* is all the more abundant as the suction is stronger; when the motor or the blow pipe are not in operation the production of gas is interrupted.

95 Fig. 3 shows an apparatus in which the gas is produced by the moist air passing through the cloths *j* before it reaches the carbide contained in the box *i*. Water tight door *o* allows the loading and unloading of the carbide box. 100

Fig. 6 shows an apparatus of a more simple construction than those previously described in which the moist air or steam flow directly in the carbide box *i* through a pipe *k* the end of which opens under a wire strainer *l* which keeps 105 back the carbide mass in the container *i* and allows the passage through said strainer *l* of the spent lime which is discharged automatically at *m*.

110 In that case the water is produced by means of

the condensation of the steam when the combustion gases escape.

The apparatus shown in Fig. 6 is mounted with a Cardan joint at *n* and is designed more especially for aerial navigation.

In the mode of execution shown in Fig. 7 the apparatus comprises a receiver *a* filled with water in which blocks of porous material *p* are immersed, the level of the water being indicated by a tube *N* placed on the outside. A carbide box *i* is engaged in said receiver which is closed in front by a gate *o* which is provided with a water-tight packing *o*¹ and is strongly pressed in position by means of an eccentric lever *q*.

The receiver is provided with an extension *a*¹ in which is arranged a tube *r* in communication on the one part with the cylinder *i* and opening on the other part in a strainer *t* retained by means of a plug. Said receiver is also provided with a second extension *k* for the admission of air from the atmosphere and with a third extension *a*², the opening of the carbide box *i* being situated underneath. The extension *a*² which is closed by means of a stopper contains a cylinder *s* provided with openings fitted with a wire grating to constitute a strainer *s*¹ designed to prevent particles of lime being drawn away in the gas discharge tube which is branched upon the third extension *a*².

The air flowing in at *k* is moistened as it comes in contact with the porous material, it then passes through the strainer *t*, the tube *r* and the box *i* from where it passes on the carbide. The acetylene gas produced is drawn out at *f*.

In the modified form shown in Fig. 8 which is more especially designed for aircraft motors, the receiver *a* is provided with two pipe systems *u* for the combustion gases which enter in the midst of the porous material. The condensation of the water steam contained in said gases is ensured by a set of tubes *v* through which flows an air stream. Air is admitted at *k*. The receiver *a* is connected with the carbide box *i*

in such a manner that the moistened air passes through the carbide layer. The acetylene gas is discharged at the top through *f*. The carbide being supported on the strainer *10* the lime dust which is produced falls to the bottom of the apparatus and is discharged by means of a suitable plug, not shown.

It is a known fact that acetylene gas is most advantageous for use in aircraft motors for the following reasons:

1. The possibility of utilizing heavy and cheap carburetting materials.

2. The great economy in calories which is realized owing to the complete vaporization in the cylinder of the heavy carburization material due to the heat of its flame.

3. The ignition takes place very easily.

The apparatus according to the present invention may therefore be advantageously used in connection with motors and blow pipes, it being thoroughly safe in operation and completely self operating. Owing to the fact that it does not give any excess of production, the consumption of acetylene gas is consequently smaller than in existing apparatus, it does not require any pressure, moreover as there are neither valves nor reducing valves there is consequently no adjustment required.

What I claim and desire to secure by Letters Patent of the United States is:—

In an acetylene gas generator, a water reservoir, a chamber for calcium carbide, a tube extending downwardly into the water of the reservoir, an injector connected to the atmosphere and opening into the calcium carbide chamber, the tube being connected with the injector, a direct connection between the carbide chamber and the water chamber, a gas outlet conduit extending below the water of the water reservoir, a float in the water reservoir having a gas outlet opening above and closely adjacent the water level, and a flexible conduit between said float and outlet conduit.
